UNITED STATES PATENT OFFICE.

JOSEPH JAKSA, OF GRAND RAPIDS, MICHIGAN, ASSIGNOR TO SOCIETY OF THE REDEMPTORIST FATHERS, OF GRAND RAPIDS, MICHIGAN, A CORPORATION OF MICHIGAN.

HOST-CUTTER.

1,139,766.

Specification of Letters Patent. Patented May 18, 1915.

Application filed September 25, 1913. Serial No. 791,725.

To all whom it may concern:

Be it known that I, JOSEPH JAKSA, a citizen of the United States of America, residing at Grand Rapids, in the county of Kent 5 and State of Michigan, have invented certain new and useful Improvements in Host Cutters; and I do hereby declare the following to be a full, clear, and exact description of the invention, such as will enable others skilled in the art to which it appertains to 10 make and use the same.

My invention relates to improvements in host cutters, and is especially adapted for cutting disks for forming what is known as 15 "the host," used by the Roman Catholic Church. The material is first formed in thin sheets and then cut in to small disks which eventually constitute the host.

The object of my invention is to provide 20 a device that will operate rapidly; having a multiplicity of cutters, any one or more of which can be put out of operation as occasion may require, and to provide the device with various new and useful features herein- 25 after more fully described and particularly pointed out in the claims.

My invention consists essentially of a table having openings therein to permit the disks to drop through the same, a clamp to 30 hold the sheet to be cut, a spring supported frame carrying the clamp, a series of rotary cutters, belt gearing to rotate the cutters, and means for disconnecting one or more of said cutters from the gearing as occasion 35 may require, as will more fully appear by reference to the accompanying drawings, in which:—

Figure 1 is a side elevation of a preferred form of my invention with portions broken 40 away to show the construction; Fig. 2 a plan view of a portion of the same, the table being omitted; Fig. 3 a horizontal section on the line 3—3 of Fig. 1; Fig. 4 a vertical section on the line 4—4 of Fig. 3, showing 45 the device out of action. Fig. 5 showing the same in action; and Fig. 6 a sectional detail of the means for putting the individual motors out of action.

Like numbers refer to like parts in all of 50 the figures.

1 represents a table of suitable dimensions having openings therein beneath the respective cutters to permit the disks to pass downward therethrough into any suitable receptacle, (not shown).

2 represents a vertically movable clamp to engage the margins of the sheet to be cut, and clamp the same securely to the table, and having openings corresponding to the openings in the table through which the cutters operate. This clamp is carried by cross bars 3 connected to the same by posts 4. These bars are supported by pins 5 extending upward therefrom and vertically slidable therein, and surrounding the said pins 60 are springs 7 to yieldably force the clamp 2 in contact with the material. The head 6 is carried on posts 8 vertically slidable in the table 1 and connected below the same by a yoke 9, to which is connected by means of 70 a chain 10, any convenient treadle (not shown) for depressing the head.

11 is a spring surrounding one of the posts 8 and yieldably supporting the head and parts connected thereto in raised position. 75 Below the head 6 and attached thereto is a bearing plate 12. Journaled in the head and plate and vertically adjustable therein are a suitable number of spindles 13 properly located, six being shown, each carrying at 80 the lower end a rigid arm projecting radially therefrom and having a downwardly projecting cutting spur or point for cutting the small disks, and a seventh spindle 13^a is provided also carrying a similar arm and 85 cutter 14^a of greater radius for cutting larger disks, and a stripper plate 13^b is provided on the end of this seventh spindle. Each spindle is provided with a pulley 15, the pulley 15^a on the spindle 13^a being larger 90 than the other pulleys. The spindles are all driven by any suitable motor 16, (an electric motor being shown), the driving pulley 16^a being elongated to permit vertical movement 95 thereon of the driving belt 17 as the driven pulleys move vertically. 18 is a tightener for the said belt mounted on an arm 19 adjustably mounted on the upper end of the post 8, which post projects through the head 6 to receive the arm. To connect each spindle with its respective pulley, each pulley is provided with a stud 20 having a head thereon, and a pin 21 is inserted through the spindle and engages the stud beneath the head 100 to drive and depress the spindle. To put a spindle out of action the pin is disconnected from the stud and the spindle raised a suitable distance and held in position by a thumb screw 22 in the head 6 engaging the 105 spindle.

110

The operation of my device is as follows: The material to form the host is first prepared by rolling the same to a sheet of suitable thickness, as at 23, and is fed step by step over the table and under the clamp as shown in Fig. 4. By depressing the head 6 the rapidly rotating spurs or points forming cutters 14 and 14^a are brought in contact with the material and the weight of the same, together with the spindles and pulleys, will be sufficient to properly feed the cutters downward to smoothly sever the material which will thus be cut by the rotating cutters to form the disks 24, (see Fig. 5) which will drop through the opening in the table 1, their detachment from the sheet being insured by the thrust of the ends of the spindles which project opposite the cutters.

If, for any reason, as for instance, in cutting narrower strips of material, it is desired to put any of the cutters out of action, this may be done as heretofore described without interfering with the operation of the remaining cutters. It is also obvious that a greater number of spindles and cutters may be provided, constituting a larger machine having greater capacity if preferred, and that the machine is also adapted to cutting disks of various other material if preferred.

What I claim is:—

1. A host cutter, comprising a table having an opening therethrough, rotary spindles yieldably supported above the table and each provided with a downwardly projecting spur or point forming a cutter, means for depressing the spindles and means for simultaneously rotating the same.

2. A host cutter, comprising a table having openings therethrough, a spring supported head above the table, means for depressing the head, a series of spindles journaled in the head, a clamp yieldably carried by the head, adapted to hold the material upon the table, downwardly projecting spur cutters on the respective lower ends of the spindles and belt gearing to simultaneously rotate the spindles.

3. A host cutter, comprising a table, a vertically movable head above the table, a spring yieldably supporting the head, spin-

dles journaled in the head and longitudinally movable therein, cutters on the lower end of the respective spindles, pulleys rotatable on the spindles, a stud in each pulley, a pin in each spindle to engage the stud and detachable therefrom and thumb screws in the head to engage and hold the respective spindles out of action.

4. A host cutter, comprising a table, posts vertically slidable in the table, a head carried by the post, a spring to yieldably support the head, a series of spindles journaled in the head, a downwardly projecting spur cutter on the lower end of each spindle, a clamp carried by the head, springs between the clamp and head to yieldably depress the clamp toward the table, and belt gearing to drive the spindles.

5. A host cutter, comprising a table having an opening therein, a vertically movable head above the table, spindles journaled in the head, rotating spur cutters on the spindles, a spring to support the head, means for depressing the head, a clamp on each side of the opening in the table, cross bars connecting clamps, pins fixed in the head supporting the cross bars and slidably therein, springs between the bars and the head and belt gearing for rotating the spindles.

6. A host cutter, comprising a table having an opening therein, posts vertically slidable in the table, a head carried by the posts, a spring yieldably supporting the head, means for depressing the posts and head, a bearing plate supported below the head, spindles journaled in the plate and head, a downwardly projecting spur cutter on the lower end of each spindle, a clamp on each side of the opening in the table, posts and cross bars supporting the clamp, pins carried by the head supporting the cross bars and slidably therein, springs between the cross bars and head and means for simultaneously rotating the spindles.

In testimony whereof I affix my signature in presence of two witnesses.

JOSEPH JAKSA.
